(57) **CLAIM**

The ornamental design for computer mouse, as shown and described.

DESCRIPTION

FIG. 1 is a perspective view of a computer mouse showing our new design;

FIG. 2 is a top plan view thereof;

FIG. 3 is a bottom plan view thereof;

FIG. 4 is a left elevational view thereof;

FIG. 5 is a right elevational view thereof;

FIG. 6 is a front elevational view thereof; and,

FIG. 7 is a rear elevational view thereof.

1 Claim, 4 Drawing Sheets
